GRILLE MATERIAL

Judson Earl Fuller, River Forest, Ill., assignor to The Harrington & King Perforating Co., Chicago, Ill., a corporation of Illinois

Application January 2, 1958, Serial No. 49,100

Term of patent 14 years

(Cl. D54—2)

Fig. 1.

Fig. 2.

Fig. 3.

Fig. 1 is a front view of a corner of a grille material showing my new design. The stripes with flashing represent a shiny appearance and the line shading on the remainder represents a contrasting finish. The balance of the material is like that shown.

Fig. 2 is an edge view looking downwardly at the representation of Fig. 1, and

Fig. 3 is a cross-sectional view taken at the line 3—3 of Fig. 1.

I claim:

The ornamental design for a grille material, substantially as shown and described.
